ATTORNEY

UNITED STATES PATENT OFFICE.

FREDERICK FLAD, OF PHILADELPHIA, PENNSYLVANIA.

CIGAR-TIP CUTTER.

SPECIFICATION forming part of Letters Patent No. 276,964, dated May 1, 1883.

Application filed November 22, 1882. (No model.)

To all whom it may concern:

Be it known that I, FREDERICK FLAD, a citizen of the United States, residing in the city and county of Philadelphia, State of Pennsylvania, have invented a new and useful Improvement in Cigar-Tip Cutters, which improvement is fully set forth in the following specification and accompanying drawings, in which—

10 Figure 1 is a top view of the cigar-tip cutter embodying my invention. Fig. 2 is a side elevation thereof. Fig. 3 is a section in line α α , Fig. 2, illustrating the operation of the cutter. Fig. 4 is a view of the piece from which the cutter is formed.

15 Similar letters of reference indicate corresponding parts in the several figures.

My invention consists of a cigar-tip cutter which is light, strong, durable, and inexpensive, the construction being hereinafter fully set forth.

Referring to the drawings, A represents the cutter, which is formed of a single piece of steel or other suitable metal, the shape of which is shown in Fig. 4, said piece being bent, near each end, into somewhat loop form, as at a , the end portions, b , thus projecting at a right angle to the main length of the piece, the edge of each portion having a semi-cylindrical opening, c . The piece is bent or folded at the middle of its length, as at d , whereby the two end portions, b , overlap and form the jaws of the cutter, the two openings c producing a single opening, c' , for the reception of the tip of a cigar, the edges of said opening being sharpened, so as to sever said tip from the body of the cigar when the jaws are forced together. It will be seen that, owing to the bent or looped portions a , the jaws b are held sufficiently separate in order to keep the opening c' uncovered, and said portions become the spread or flaring sides a' of the cutter, which may be engaged by the thumb and forefinger of the hand of the operator for advancing the jaws 45 toward each other, the sides also being elastic or constituting springs, whereby they return to their normal position. The portions of the sides adjacent to the fold or bend d are firmly pressed together, so as to be somewhat flattened and produce the handle e of the device.

When service of the cutter is required the handle portion e is grasped and the cutter presented to the cigar, the tip whereof is introduced into the opening c' . The thumb and

forefinger are then slipped toward the jaws b along the sides a' and pressed against the latter, whereby the cutting-edges of the opening c' are forced through the cigar in opposite directions and nicely sever the tip therefrom. The sides a' are then let go, whereby the parts 60 are restored to their normal position, and the operation of tip-cutting may be repeated when desired.

It will be seen that as the jaws b overlap and rest one on the other they are guided in 65 their advancing and returning motions, so that they cut the cigar smoothly and uniformly. The handle portion e , serving as the starting-point of the operation of the device, tends to locate the thumb and forefinger, so they do not slip from the device when first grasped, which would be occasioned if first applied to the sides a' , which are polished, and also prevents the premature motion of the jaws, such motion being accomplished after the cigar-tip 75 has entered the opening c' , the thumb and forefinger then riding properly on the spread or flaring sides and pressing them together, the result of which has already been stated.

It will also be seen that the cutter has no 80 rivets or fastening-pieces, is simple in construction, and alike strong, durable, and inexpensive. In the handle portion is an opening for the attachment of the device to a watch-chain, cord, &c., said opening being formed directly 85 in the metal of the handle, whereby the attaching or suspension ring of the watch-chain, &c., is prevented from shifting and entering the jaw end of the device.

I am aware that it is not new to form a cigar-cutter of one piece of metal embodying cutting-jaws and flaring sides and a curved portion opposite the jaws forming an open eye in which the watch-chain ring is fitted, and therefore disclaim such features.

Having thus described my invention, what I 95 claim as new, and desire to secure by Letters Patent, is—

A cigar-tip cutter formed of a single piece of metal, consisting of cutting-jaws b c , flaring 100 sides a' , and portions e e , which latter are flattened together and held in contact and perforated, substantially as and for the purpose set forth.

FREDERICK FLAD.
